Max Obrist, Long Island, N. Y., assignor to Tos-
cny Fabrics Inc., New York, N. Y., a corpora-
tion of New York

Application June 14, 1949, Serial No. 3,270

Term of patent 3½ years

(Cl. D92—1)

To all whom it may concern:

Be it known that I, Max Obrist, a citizen of the United States, residing in Long Island, county of Queens and State of New York, have invented a new, original, and ornamental Design for a Plastic Film Material, of which the following is a specification, reference being had to the accompanying drawing, forming a part thereof.

The figure of the drawing is a plan view of a plastic film material, showing my new design.

I claim:

The ornamental design for a plastic film material, as shown.

MAX OBRIST.
